INVENTOR:

John L. Grotling

UNITED STATES PATENT OFFICE.

JOHN L. CREVELING, OF TUCSON, ARIZONA, ASSIGNOR TO GOULD COUPLER COMPANY, A CORPORATION OF NEW YORK.

ELECTRIC SYSTEM.

1,336,619.

Specification of Letters Patent. Patented Apr. 13, 1920.

Application filed October 7, 1916. Serial No. 124,355.

To all whom it may concern:

Be it known that I, JOHN L. CREVELING, a citizen of the United States, residing in Tucson, Arizona, have invented certain new and useful Improvements in Electric Systems, of which the following is a description.

My invention pertains to that class of electric systems used in connection with prime movers to assist in the proper operation of the prime mover.

My invention is particularly applicable to systems employing a prime mover of the internal combustion type wherein the explosive mixture is fired by means of an electric spark normally caused by current generated by a dynamo electric machine driven by the prime mover and subject to wide variations in speed.

My invention is particularly applicable to such systems wherein the engine has to be stopped and started or driven at low speed, and wherein it is therefore desirable that the field strength of the spark producing dynamo should at times be as great as possible and at other times somewhat weaker for the purpose of regulation for speed changes, and wherein insurance of correct magnetic polarity of the field is desired.

In the drawing, Figure I is a diagrammatic representation of one type of system embodying the essentials of my invention.

Fig. II is a diagrammatic representation of the system of Fig. I during a different phase of its operation than depicted in Fig. I.

In Fig. I, 1 diagrammatically illustrates a pair of the usual sparking points such as are provided in the usual commercial spark plug. As many spark plugs, of course, as are necessary may be provided for the prime mover, and any suitable type of distributing means may be used for placing them in circuit with the secondary 2 of any suitable type of induction coil or transformer which may be connected up as usual with its remaining terminal grounded as indicated. The primary winding 3 has one of its terminals connected as by wire 4 with a brush 5 in electrical communication with the segment 6 of a special two-segment commutator, the function of which will hereinafter more plainly appear. The segment 6 is connected with the winding 7 diagrammatically shown as a single inductor carried by the

armature structure 8. The opposite end of the winding 7 is connected with any suitable type of slip ring as indicated at 9, from which the wire 10 is carried to a make and break device or pair of contact points indicated at 11 and operated by any suitable type of cam connected with the prime mover and indicated at 12. The wire 13 is carried from one side of the make and break device 11 to the brush 14 bearing upon the segment 15 of the commutator, which is in communication with the brush 16 which may be grounded as indicated at 17. The winding 7 may be of any suitable type for producing a proper ignition current, but I prefer to use a two-part commutator in connection therewith and operate in a bi-polar field, and for this reason prefer to employ the usual magneto or shuttle type of winding. The armature structure 8 is provided with a suitable direct current winding which may be of any desired type connected with the commutator 18, the positive brush of which is connected as by wire 19 with the remaining terminal of the primary winding 3, while the negative brush may be grounded as by wire 20. 21 is a shunt field winding for the dynamo which may be directly in shunt across the brushes, if desired. 22 is a differential winding having one terminal connected as by wire 23 with the wire 19, and its opposite terminal connected as by wire 24 with the positive side of the storage battery 25 and lamps or other translating devices as indicated at 26. The negative terminals of the battery 25 and translating devices 26 may be grounded as indicated at 27. The coil 22 opposes the magnetomotive force of the coil 21 when traversed by current from the generator to the battery 25 and assists the winding 21 when current flows from the battery 25 back through the coil 22. Any suitable type of switch may be used for cutting the generator into circuit when the voltage is slightly above that of the battery, and cutting it out of circuit when its voltage falls slightly below that of the storage battery, and may be placed for example in the lead 19, as indicated. It is obvious that any suitable switch may also be used for preventing the battery current from flowing through the primary ignition circuit when the prime mover is at rest and current is not wanted, and may for example to be placed as indicated in wire 28.

As the particular types or positions of these switches are not a part of my present invention, all details thereof are purposely omitted for the sake of brevity, and it is intended merely to indicate the presence of proper devices for the purposes indicated and which may be placed where most desirable.

In Fig. II like numerals are used to indicate like parts, but the armature structure 8 is shown in such position that the inductor 7 is setting up an electromotive force in a direction opposed to that indicated in Fig. I, and the commutator connected therewith is in proper position for this phase of operation, and it will be noted that the brushes 5 and 14 are now in electrical communication with each other through segment 15 of the commutator, while segment 6 of the commutator, connected with the end of the winding 7, is in electrical communication with the brush 16.

An operation of my invention is as follows:

Supposing the prime mover to be running at a normal operating speed and the dynamo electric machine therefor operating also at a normal speed, and that when the armature 8 is in the position diagrammatically portrayed in Fig. I the electromotive force set up in the winding 7 is in the direction of the arrows indicated thereupon, then current will flow from the winding 7 to the slip ring 9, wire 10, make and break device 11, wire 13 and brush 14 to the segment 15, and thence from brush 16 to ground, and from ground to wire 20, through the direct current windings upon the armature structure 8, through wire 19, wire 28, primary winding 3, wire 4, brush 5, to commutator segment 6, and thence back to the winding 7. And it will thus be noted that the direct current windings upon the armature structure 8 and the ignition winding 7 upon the said armature structure 8 are operating in series with each other, in such manner as to increase the electromotive force impressed across the terminals of the primary winding 3. Current will also flow from the direct current windings upon the structure 8, through wire 19, wire 23, coil 22 and wire 24 to the storage battery 25 and lamps or other translating devices 26, when such are in circuit, and return from these devices will be through the ground, as indicated at 27, to the ground connection of the direct current winding through wire 20. The current passing through coil 22 to the storage battery and translating devices will oppose the magnetomotive force of the shunt or energizing coil 21 in such manner as to hold the generator output which traverses the said winding 22 from exceeding to any considerable degree a predetermined maximum current throughout wide increases in speed, as

is well understood in the art, and therefore the entire system is regulated automatically with sufficient accuracy for practical purposes throughout all the speed changes to be met with from the critical operating speed to the maximum speed to be attained.

In that phase of the operation shown in Fig. II, the direct current windings of the armature 8 and their coöperating parts of the system will operate as outlined above with respect to Fig. I, but the electromotive force set up in the inductor 7 will be in the opposite direction, as indicated by the arrows thereupon, and current will now flow from inductor 7 to segment 6, and through brush 16 to ground, and return through wire 20, direct current windings upon the structure 8, wire 19, wire 28, primary winding 3, wire 4 and brush 5 to segment 15, and then to brush 14 through wire 13 to contact device 11, then through wire 10 and collector 9 to the inductor 7. And it will be noted that while the connection between the inductor 7 and the direct current windings of the armature 8 has been so altered that the electromotive forces of both sets of armature windings are additive and in the same direction with respect to their external circuit, the current traversing the make and break device 11 has its direction reversed, which will prevent uneven wearing or burning away of the contact points. Throughout increases in speed above the normal, the above outlined operation will be continued, and these operations will continue throughout decreases in speed until the armature is revolving so slowly that the direct current windings set up an electromotive force only approximately equal to that of the storage battery when a portion of the current then supplied to the circuit containing the primary 3 will be supplied by the battery operating in multiple with the direct current armature windings. This current will flow back through the winding 22 in such manner as to increase the field excitation and tend to keep up the voltage of the direct current winding so that the same will equal that of the battery at as low speed as possible, and this increase of the field strength will also increase the voltage generated by the inductor 7 and tend to increase the sparking current caused thereby, and thus assist in compensating for the lower armature speed. If the speed falls still lower, the voltage of the direct current windings will be below that of the battery and the automatic switch will cut out the direct current windings to prevent current being wasted by flowing back through the same from the battery, and under these conditions the battery will then operate alone in series with the inductor 7 to supply the spark producing current in the primary 3, which will continue to flow through the winding 22 in such direction as

to tend to increase the electromotive force generated in the winding 7, and also tend to cause the direct current windings to reach their normal voltage at as low speed as possible.

From the foregoing it will be noted that I have produced a system wherein the alternating current inductors always are assisted either by the battery or the direct current 10 windings to cause a high electromotive force to be impressed upon the primary 3, and that at low speed the magnetic field is strengthened so as to increase the electromotive force set up in both sets of inductors 15 whereby the electromotive force impressed upon the primary winding 3 is greater than usual throughout wide changes in speed, and that by automatically and simultaneously reversing the current through the 20 make and break points I eliminate considerable of the usual wear upon the same.

I do not wish in any way to limit myself to any of the exact constructions or details of operation given above to illustrate one 25 embodiment of my invention, for it will be obvious that wide departure may be made without departing from the spirit and scope thereof.

I am acquainted with application No. 30 38,848 of John W. Jepson, and it is not intended to herein claim any of the subject-matter of said application.

What I claim is:

1. In a system of the class described having an ignition circuit with a battery, an ignition armature and interrupter in said circuit, a commutator acting to control the connections between the battery and said ignition armature to maintain the voltage 40 of each in uniform direction to build up the ignition circuit, and means whereby current flowing from the battery to said ignition circuit assists in increasing the electromotive force set up by said ignition armature.

2. In a system of the class described having an ignition circuit with a battery, an ignition armature and interrupter in said circuit, a commutator acting to control the connections between the battery and said ignition armature to maintain the voltage of each in uniform direction to build up the ignition circuit, and means whereby current flowing from the battery to said ignition circuit assists in increasing the electromotive force set up by said ignition armature combined with armature windings connected in circuit with the battery to charge the same, and assisted by said battery.

3. In a system of the class described having an ignition circuit with a battery, an ignition armature and interrupter in said circuit, a commutator acting to control the connections between the battery and said ignition armature to maintain the voltage 65 of each in uniform direction to build up

the ignition circuit, and means whereby current flowing from the battery to said ignition circuit assists in increasing the electromotive force set up by said ignition armature combined with armature windings connected in circuit with the battery to charge the same, and assisted by said battery when supplying current to the ignition circuit.

4. In a system of the class described, the combination with a generating armature, 75 a battery and an ignition circuit in operative relation, an induction means having its primary in series in said circuit and its secondary connected to supply ignition devices, means controlling the connections between 80 the battery and the armature to maintain their electromotive forces additive when conjointly supplying the current to the induction means, and means whereby the current from the battery also tends to augment the 85 electromotive force of the generating windings.

5. A system of the class described having an ignition circuit containing a battery, generating armature and induction means in 90 series, means whereby said induction means supplies current for ignition purposes, and means whereby ignition current supplied by the battery magnetically affects the generating armature.

6. The combination with ignition means, of current affected means for operating the same, an armature winding for supplying current to said means, a storage battery operating to assist said winding, and means 100 whereby ignition current from said battery magnetically affects said armature winding.

7. The combination with ignition means operated by electric current, of means for supplying current thereto comprehending 105 an armature winding and a storage battery, means whereby current may be supplied by the battery and winding acting conjointly to assist each other, and means whereby that portion of the current supplied by the battery augments the portion furnished by the armature winding.

8. The combination with ignition means operated by electric current, of means for supplying current thereto comprehending 115 an armature winding and a storage battery, means whereby current may be supplied by the battery and winding acting conjointly to assist each other, and means whereby that portion of the current supplied by the battery augments the portion furnished by the armature winding combined with armature windings for charging the said battery.

9. The combination with ignition means operated by electric current, of means for 125 supplying current thereto comprehending an armature winding and a storage battery, means whereby current may be supplied by the battery and winding acting conjointly to assist each other, and means whereby that 130

portion of the current supplied by the battery augments the portion furnished by the armature winding combined with armature windings for charging the said battery and affected by current flowing from said battery.

10. The combination with ignition means operated by electric current, of means for supplying current thereto comprehending 10 an armature winding and a storage battery,

means whereby current may be supplied by the battery and winding acting conjointly to assist each other, and means whereby that portion of the current supplied by the battery augments the portion furnished by the armature winding combined with armature windings for charging the said battery and affected by current flowing to and from the battery.

JOHN L. CREVELING.
